2,318,072

HIGH INTENSITY FLUORESCENT LAMP
SYSTEMWillard C. Hall, Jr., Los Angeles, Calif., assignor
to Alfred P. Daniels, Los Angeles, Calif.

Application September 24, 1941, Serial No. 412,124

6 Claims. (Cl. 176—124)

This invention relates to a system for safely increasing the illuminosity of gaseous electric discharge lamps and the like. It is especially useful for intensifying the illuminosity of fluorescent type lamps having end electrodes or cathodes which are heated to increase the flow of electrons. At present, the cathodes of such tubular lamps operate at a given current density which forms a single hot or glow spot; the character and heat of this spot largely determining the life of the lamp. Should more than the rated current pass through the cathode, the hot spot there- 10 of becomes too intense and the filament rapidly deteriorates and breaks.

This invention intensifies the illumination of standard gaseous electric discharge types of lamps by forming a plurality of hot or glow spots on the cathodes. By forming a plurality of hot spots, each hot spot does not become overheated and the filament, therefore, does not rapidly deteriorate thus each cathode safely operates at greater electronic capacity.

This invention intensifies the illumination of standard gaseous electric discharge types of lamps by forming a plurality of hot or glow spots on the cathodes. The hot spots do not tend to merge and the filament is not in any way impaired. Instead of the lamp having all its lighting energy emanating from a single spot upon the cathode, a plurality of such spots supply the energy at a 25 low temperature and forms a greater column of light giving properties throughout the active length of the lamp.

An object of this invention is to present an electrical system for greatly increasing the illumination of gaseous electric discharge lamps without shortening the useful life thereof.

Another object is the provision of a transformer device which is capable of forming a plurality of hot spots on a single cathode.

Still another object is to provide an electrical system for standard gaseous electric discharge lamps which forms a plurality of hot spots on their filaments for materially increasing the efficiency thereof at a high power factor; this being accomplished by a simple sturdy device economical to manufacture.

Other objects, advantages and features of my invention will appear from the accompanying drawing, the subjoined detailed description, the preamble of these specifications and the appended claims.

Applicant is about to illustrate and describe one of the forms of his invention in order to teach one how to make, use and vend the same, but it is

to be understood that the drawing and description thereof are not to limit the invention in any sense whatsoever, except as limited by the appended claims.

5 In the drawing:
Fig. 1 shows a wiring diagram of the invention.
Fig. 2 shows in elevational view, parts being broken away, of a switch adapted for use in the invention.

10 The reference character 1 indicates the illuminating device and the character 2, the transformer. The illuminating device in the drawing is a glass tube or envelope having at its ends the glass presses 3 and 4 through which pass the conductors 5 and 6, and the conductors 7 and 8 respectively. Within the envelope are the electrodes or thermionic cathodes 9 and 10 in the form of coiled filaments having their ends connected across the lead in conductors at their respective ends of the tube. The tube is filled with a low pressure rare gas such as neon or argon and a few drops of a vaporizable metal such as mercury. The inner side of the walls of the tube are coated with a fluorescent material which materially brightens the lamp since the electrical discharge between the electrodes is scarcely visible.

15 The transformer comprises a plurality of laminated limbs, a large area central limb 11 upon which is wound the primary coil 12. This coil has leads 13 and 14 at its ends which connect with a source of suitable electric pulsating current not shown. A hand switch 14' is shown in the lead 14.

20 Outer limbs 15 and 16 of the transformer have secondary coils 17 and 18 respectively wound thereon. The laminated bars 19 and 20 complete the magnetic path of the transformer. The coil 17 has one end connected to the conductor 5 and the other end to conductor 7. Shunting the coil 17 are the switch 21 having leads 21' and 21'' and the condenser 22 with its leads 22' and 22''. The other secondary coil has one end connected to the conductor 6 which leads to the cathodes 9, and the other end of which that connects with the conductor 8; the conductor 8 leading to the other cathode 10.

25 The instantaneous polarity of the secondary coils are indicated, and show that the instantaneous positive polarity of each coil is connected across one of the electrodes and the instantaneous negative polarity of each coil is connected across the other electrode. Therefore, when an alternating current; for instance, at an impressed line voltage of 110 and frequency

of 60 cycles, is connected to the primary 12 through switch 14, like voltages and polarity, at any given instant, is impressed across one of the electrodes, and the opposite polarity across the other electrode. This is the case when the tube is in normal operation by electronic bombardment.

To start the tube, the switch 21 and condenser 22 must function so as to first heat the cathodes and provide the higher voltage surge to strike the tube. The switch 21 may be of the gaseous electric discharge type now to be described, or it may be of the type that is closed when cold and open when hot.

In Fig. 2 of the drawing, a gaseous electric discharge switch is shown which is especially adapted for use in this invention. The switch has a casing or envelope 27 which may be of glass or metal, and has the glass press or seal 28 which give support to the two bimetal strips 29 and 30, the strips having connection with the wire conductors 21' and 21" as shown in Fig. 1. One of the strips has a curled contactor 31 and the other strip has a plate contactor 32. The envelope is filled with any suitable ionizable gas such as neon. When current at proper voltage is connected across the leads of the switch, an electric discharge will take place between the strips 29 and 30 and heat them. Upon heating, the strips will flex toward each other and their ends make contact to close the circuit; contact having been made, the switch strips 29 and 30 cool and separate and thus open the circuit to which they are connected. This switch when closed, at the start of operations, short circuits the coil 17 and thus doubles the power out-put and voltage of coil 18 which is then in series with both electrodes and provides the current to heat these electrodes. When the filaments of these electrodes become hot, the switch 21 automatically opens (a matter of a few seconds) and connects like polarity ends of both coils to their respective electrodes. Immediately, the electrodes have opposite polarity at any instant, and are maintained at operating heat by electronic bombardment alone.

By the arrangement of this new system, two hot spots form on each electrode at their ends as indicated by the numerals 23, 24, 25 and 26. These spots form conductive gas columns in the tube which merge to form an intensified principle conductive column which extends the major length of the tube. The spots on each electrode do not tend to unite due to the resistance along the filament being greater than the ionized gas column. This action means that it is possible to run the tube at twice its normal current capacity and hence obtain nearly twice its normal brilliancy without injury to the cathodes or tube. Therefore, the life of the tube is not shortened since two emissive spots are formed on each cathode instead of the usual one.

Having thus described my invention, what is claimed as new and desired to be secured by Letters Patent is:

1. In combination, a gaseous electric discharge lamp with end cathodes and a transformer, the transformer having a primary coil, and secondary windings substantially in phase with their like polarity ends connecting across one cathode and the other opposite like polarity ends connected across the other cathode, and switch means connected across one of the windings to short it when the lamp is started.
- 10 2. In combination, a gaseous electric discharge lamp with end cathodes and a transformer, the transformer having windings substantially in phase with their like polarity ends connecting across one cathode and their other opposite like polarity ends connected across the other cathode, a switch and condenser having leads connecting opposite ends of one of the windings, the switch operating to short the winding when closed, and a primary coil for energizing the windings.
- 15 3. In combination, a gaseous electric discharge lamp with end electrodes and a transformer, a primary winding for supplying power to the transformer, a plurality of secondary coils, the ends of the coils having like polarity connecting across one of the electrodes and the other ends of the coils connecting across the other electrode, switch means for short circuiting one of the coils to allow the other coil to heat the electrodes in series.
- 20 4. In combination, a gaseous electric discharge lamp with end cathodes and a transformer having three limbs, a primary winding on one of the limbs having connection to a source of electric current, a secondary coil on each of the other two limbs, a conductor from one end of each coil connected across one of the cathodes and another conductor from the opposite end of each coil connected across the other cathode, a switch connected across one of the coils for the purposes described.
- 25 5. The method of forming a plurality of hot spots on the cathodes of a gaseous electric discharge lamp by: providing across each cathode a like instantaneous polar voltage and maintaining the cathodes in opposite instantaneous polarities with respect to each other, and maintaining the spots on the cathodes separated by maintaining a lower resistance between the cathodes than between the spots.
- 30 6. In combination, a gaseous electric discharge lamp with a plurality of electrodes and a transformer having a primary coil and secondary windings, two of the electrodes each including a filament having spaced apart hot spots, one of the filaments having its ends connected across like polarity parts of said windings and the other filament having its ends connected across the opposite like polarity parts of the windings, and switch means connected across one of the windings to short it when the lamp is started, the shorting of said one of the windings connecting the other winding in series with said filaments.
